UNITED STATES PATENT OFFICE.

DAVID FITZPATRICK, OF CLEVELAND, OHIO, ASSIGNOR TO THE CLEVELAND WORM & GEAR COMPANY, OF CLEVELAND, OHIO.

WORM-GRINDING MACHINE.

1,340,030.

Specification of Letters Patent. Patented May 11, 1920.

Application filed August 2, 1915. Serial No. 43,175.

To all whom it may concern:

Be it known that I, DAVID FITZPATRICK, a citizen of the United States, and resident of Cleveland, in the county of Cuyahoga and State of Ohio, have invented certain new and useful Improvements in Worm-Grinding Machines, of which the following is a specification.

My invention relates to a machine for 10 grinding worms or similar machine parts having convolute threads.

At the present time worms are machined to size by means of hobbing tools. In some cases, however, it is necessary to temper the 15 worm after it has been cut, and in the hardening process inaccuracies are almost certain to develop. The object of the present invention is to provide a machine which will automatically and accurately grind the 20 worm to size after it has been tempered.

In a worm cutting machine the length of time required for the hobbing tool to make 25 a complete cut through one thread is so great that the time element is not a matter of great importance. Therefore, at the end 30 of a cutting travel of the hobbing tool the operator backs the tool away from the worm by hand, indexes the worm by hand, reverses the machine by hand, and runs the tool back to the other end of the worm, and then draws the tool into cutting position and starts it on its forward travel.

On the other hand, with a grinding machine, the grinding wheel may pass through 35 the worm in a few seconds and the time consumed in making the various changes by hand, as is done in the cutting machine, would be a matter of considerable importance.

40 In other words, in a cutting machine, if it took an hour to make each cut, a matter of three or four minutes consumed in making the changes would be of minor importance, and the machine would be doing work the greater part of the time.

On the other hand, in a grinding machine, if it took fifteen seconds to make a cut, a matter of three minutes in making the changes would be of substantial importance, 50 and the machine would be doing work only a relatively small portion of the time. Therefore, in a grinding machine it is essential that as many as possible of the operations be performed automatically.

55 According to my invention all of the changes may be made automatically, but I

prefer to utilize manual means for adjusting the depth of cut to be taken by the grinding tool from time to time as the worm is being ground.

60 In the preferred form of my invention the grinding wheel is moved longitudinally with respect to the worm, but I do not limit myself to this form of construction. In this preferred form the apparatus automatically 65 performs a cycle of movements. The grinding wheel passes through one thread of the worm in grinding contact therewith. It is then withdrawn and the worm indexed by advancing it one thread. The whole machine is then reversed, and the grinding wheel travels back across the worm but out 70 of contact therewith until it reaches the limit of its travel, when it is brought forward into grinding contact and the cycle 75 of operations repeated. It is only necessary for the operator to occasionally advance the tool slightly so as to take a deeper cut.

Various other objects and advantages of 80 the invention will be in part obvious from an inspection of the accompanying drawings and in part will be more fully set forth in the following particular description of one form of mechanism embodying the invention, and my invention also consists in certain 85 new and novel features of construction and combination of parts hereinafter set forth and claimed.

In the accompanying drawings:

Figure 1^A is a front elevation of a completed machine disclosing a preferred embodiment of my invention;

Fig. 1^B is an enlarged detailed view of the upper portion of the reversing wheel shown at the front of the machine in Fig. 1^A;

Fig. 1^C is a transverse sectional view taken on the line 1^C—1^C of Fig. 1^B looking in the direction indicated by the arrows;

Fig. 1^D is an enlarged sectional view taken on the line 1^D—1^D of Fig. 1^B;

Fig. 1^E is a view partially in front elevation and partially in section on the line 1^E—1^E of Fig. 1^B;

Fig. 2^A is an end elevation of the right side of the machine shown in Fig. 1^B with the pulley and its driving belt omitted;

Fig. 2^B is a longitudinal sectional view taken axially through the emery wheel spindle and taken on the line 2^B—2^B of Fig. 2^A;

Fig. 3^A is a view similar to Fig. 2^A showing the opposite or left end of the machine;

Fig. 3^B is an enlarged sectional view taken

- 2
- on the line 3^B—3^B of Fig. 3^D and on the similar lines in Fig. 6^B;
- Fig. 3^C is a transverse sectional view taken on the line 3^C—3^C of Fig. 3^B;
- 5 Fig. 3^D is an end view of the parts shown in Fig. 3^B;
- Fig. 3^E is a view similar to that shown in Fig. 3^D with the stop plate in rotating position;
- 10 Fig. 4^A is a view of the rear elevation of the machine;
- Fig. 5^A is a plan view of the machine;
- Fig. 5^B is a view similar to Fig. 5^A with certain superstructures removed to expose 15 the interior parts of the machine;
- Fig. 5^C is a horizontal sectional view taken on the lines 5^C—5^C of Figs. 4^A and 6^A;
- Fig. 6^A is a longitudinal vertical sectional view taken on the line 6^A—6^A of 20 Fig. 5^A;
- Fig. 6^B is a transverse vertical sectional view taken on the line 6^B—6^B of Figs. 6^A and 5^A;
- Fig. 6^C is a plan view partly in section 25 of the worm-work showing an adjacent portion of the emery wheel in grinding position relative thereto;
- Fig. 6^D is a view similar to Fig. 6^C showing the relative positions of the work and 30 emery wheel when in the return traverse position;
- Fig. 7^A is a transverse vertical sectional view taken on the line 7^A—7^A of Fig. 5^A, approximately at the center of the machine;
- 35 Fig. 7^B is a vertical transverse sectional view taken on the line 7^B—7^B of Fig. 5^B;
- Fig. 7^C is a view similar to Fig. 7^B taken on the line 7^C—7^C of the Fig. 5^B;
- Fig. 7^D is a fragmentary plan view of the 40 tool head partly in section on the line 7^D—7^D of Fig. 7^A;
- Fig. 8^A is a vertical longitudinal sectional view at the back of the machine, taken on the line 8^A—8^A of Fig. 5^B;
- 45 Fig. 8^B is a vertical sectional view through parts of the tool head, taken on the line 8^B—8^B of Fig. 5^A;
- Fig. 8^C is a horizontal sectional view taken on the line 8^C—8^C of Fig. 8^A;
- 50 Fig. 8^D is an enlarged plan view of the construction shown on the line 8^D—8^D of Fig. 8^E;
- Fig. 8^E is a transverse sectional view taken on the lines 8^E—8^E of Fig. 8^D;
- 55 Fig. 8^F is an enlarged view of the handle and a section of certain adjacent parts shown in Fig. 8^B;
- Fig. 8^G is a transverse sectional view taken on the line 8^G—8^G of Fig. 8^F;
- 60 Fig. 9^A is an enlarged view partly in horizontal section of certain of the driving mechanisms shown to the right of Fig. 5^B;
- Fig. 9^B is a vertical transverse sectional view taken on the line 9^B—9^B of Fig. 9^A and 65 on the similar line on Fig. 10^B;
- Fig. 9^C to 9^G inclusive are details of the reversing trip shown in section in Fig. 9^A; Figs. 9^C and 9^D being taken respectively on the lines 9^C—9^C and 9^D—9^D of Fig. 9^A; Figs. 9^D and 9^G being shown in different operative 70 positions;
- Figs. 10^A to 10^C inclusive are enlarged views of portions of the indexing mechanism shown in plane in Fig. 5^B; Fig. 10^A showing the parts when the emery wheel is in 75 its grinding position; Fig. 10^B when the parts are in their work indexing position; and Fig. 10^C when in their reverse traverse position;
- Fig. 11^A is an enlarged vertical sectional view taken through the head stock of the same parts shown in Fig. 6^A on reduced scale;
- Fig. 11^B is a horizontal sectional view taken on the line 11^B—11^B of Fig. 11^A; 85
- Fig. 11^C is a vertical sectional view taken on the line 11^C—11^C of Fig. 11^A and the similar line in Fig. 11^B;
- Fig. 11^D is an end elevation of the work plate and dog taken sectionally through 90 the work on the line 11^D—11^D of Fig. 11^A; and
- Figs. 12^A and 12^B are views respectively 95 similar to the views shown in Figs. 1^A and 5^A showing the emery wheel in position in its inoperative return.
- In the following description and in the claims, the parts will be described briefly in order to condense the specification and will be identified by specific names for convenience of expression, but they are intended to be as generic in their application to similar parts as the art will permit. Parts, the length of which extend parallel to the front of the machine, will be referred to as longitudinal members while parts extending from front to rear will be referred to as transverse members. The description of parts which are obvious from the drawings have been either condensed or altogether omitted.
- 100 Figs. 3^E, 9^G and 10^B show the position of the parts while the work is being indexed at the end of the grinding traverse; Figs. 6^D, 10^C, 12^A and 12^B show the parts while the 105 grinding wheel is on its inoperative traverse and all the other figures show the parts of the machine when the grinding wheel is operatively engaging the worm on its grinding traverse.
- 110
- 120
- Frame, head stock and tail stock.
- In the accompanying drawings, there is shown a lathe type of machine including a hollow box like supporting bed frame 40 125 (Fig. 1^A) designed to inclose most of the mechanism and extending upwardly from the left end of which is a hollow box 41 constituting the head stock of the machine. A cover plate 42 is bolted to the top of the 130

box to inclose the live center driving mechanism therein. A work table 43, provided with longitudinally extending guideways 44 (Fig. 5^A) is fixed to the front portion 5 of the top of the bed and extends from the head stock 41 to the right end of the frame 40. A longitudinally movable tail stock 45 is slidably mounted on the guideways 44 and is adjustably fastened to the work table 10 by means of bolts 46 as is usual with similar lathe constructions.

The tail stock carries a longitudinally adjustable slide 47 (Fig. 12^A) controlled by an adjusting thumb-screw 48 for moving 15 the dead center 49 to and from the live center 50 carried by the head stock. The work W is centered between the pointed ends of the live and dead centers. The dead center is locked in position bearing on the 20 adjacent end of the work by means of a clamping screw 51 carried by the tail stock and designed to bear on the side of the slide 47.

Tool carriage.

25. The upper portion of the bed 40 to the rear of the table 43 (Figs. 2^A and 7^A) and head stock 41 provides a support for a tool carriage bodily movable longitudinally 30 of the machine. This carriage includes a bottom member 52 constituting a bed plate. This bed plate is provided with a depending longitudinal guiding rib 53, V-shape in cross-section, slidably mounted in a similar 35 shaped groove formed in the top of the bed 40 and is also provided on its upper side with upstanding transverse, half dove-tail guideways 54 (Fig. 8^A) to form a broad channel therebetween, in which channel is 40 slidably fitted a transversely movable intermediate plate 55. The upper face of this plate 55 is also provided with guideways 56 paralleling the guideways 54. A grinding 45 tool supporting head 57 is adjustably mounted on the guideways 56 for movement to and from the work W (Fig. 7^A).

Drive for tool carriage traverse.

50. An L-bracket arm 58 (Fig. 5^A) projects from the right end of the machine and constitutes an out-bearing for one end of a main power shaft 59, to which power is supplied through a pulley 60 belted from any suitable source. The transmission of 55 power from the pulley to the shaft is controlled by means of a friction clutch 61 controlled by the hand lever 62 at the right front of the machine (Figs. 2^A and 5^C). A 60 45° spiral gear 63 (Fig. 6^A) fixed to the shaft 59 meshes with a similar gear 64 (Fig. 9^A) fixed to one end of a longitudinally extending shaft 65 journaled in a bracket 66 fixed to the bed frame of the machine below 65 the plate 52 (Fig. 5^A). A sliding dou-

ble clutch element 67 (Fig. 9^A) is keyed to the shaft 65 and is operable between oppositely disposed bevel gear co-acting clutch elements 68 and 69 loose on the shaft.

These bevel gear clutch elements are in 70 mesh continuously with a large vertically disposed bevel gear wheel 70 fixed to the rear end of a short forwardly extending shaft 71 which is journaled centrally in a bracket 72 (Fig. 9^B). A spur gear 73 keyed 75 to the front end of the shaft 71 meshes with a gear 74 (Fig. 7^B) mounted on a transverse shaft 75, which is provided at its rear end with a worm 76 meshing with a worm gear 77. This worm gear 77 is fixed to a 80 lead screw 78 (Fig. 5^B), extending longitudinally of the machine directly beneath the bed plate 52 and is journaled in brackets 79 and 80 at opposite ends of the bed frame 40. The lead screw is threaded through a nut 85 81 constituting a lug depending from the underside of the plate 52 and designed to feed the plate along its guideways and in a direction depending upon which of the elements 68 or 69 is connected to the driving 90 shaft 65.

Drive for turning worm.

A spur gear 82 is fixed to the left end of the lead screw 78 (Fig. 5^B) and constitutes 95 the driving element of an upwardly and forwardly extending train of gears (Fig. 3^A), four of which gears are shown for the particular type of worm illustrated. The gears are accessible from the left end of the 100 machine and the intermediate gears 83 and 84 of this train are adjustably mounted in the rocking frame 85 which is pivoted to a bracket 86 (Fig. 6^B) and which is fastened in adjusted position by means of the bolt 105 and slot connection 87 (Fig. 3^A).

The driven gear 88 of the train is fixed to a short shaft 89 (Fig. 11^B) carrying a spur gear 90 within the frame 41. The gear 90 meshes with a gear member 91 loose on a 110 longitudinally extending shaft 92. The member 91 includes a bevel gear 93 constituting the left end of a differential gear set 94. Bevel gear 93 meshes with both of the bevel gears 95, rotatably mounted on the 115 block 96 of the gear set to rotate the same when the right hand member 97 of the set is locked against rotation by the mechanism shown in Figs. 3^C to 3^E and hereinafter described. The block 96 is pinned to the 120 shaft intermediate its length. A bevel gear 98 is keyed to the inner end of the shaft 92 and meshes with a bevel gear 99 pinned to a transverse shaft 100, the forward end of which projects through the front face of 125 the head stock 41, for a purpose hereinafter described.

A worm 101 is normally clamped to the shaft 100 and meshes with a worm wheel 102 (Fig. 11^A) keyed to a live center spin- 130

idle 103 rotatably mounted in bearings 104 and in turn driving the live center 50 demountably fitted therein. The spindle has a face plate 105 fixed thereto from which 5 plate projects a pair of lugs 106 (Fig. 11^D) carrying centering screws 107 engaging opposite sides of the tail 108 of a dog 109 clamped to the adjacent end of the work by dog screw 110. By means of this mechanism 10 the work W is rotated in one direction (indicated by the arrow in Fig. 11^A) while the lead screw is advancing the tool carriage in its grinding direction toward the head stock.

15 *Mechanism for moving carriage backward.*

A rack 111 (Fig. 8^A) depends from the bed plate 52 and meshes with a large gear wheel 112 fixed to a shaft 113 (Fig. 7^A) 20 which projects forwardly through the front face of the bed frame 40 (Fig. 1^A). A toothed ratchet wheel 114 of relatively large diameter is fixed to the front end of the shaft (Fig. 1^C) in position accessible to the operator. A pair of adjustable arms 115 are pivotally mounted upon the rear hub of the wheel 114 (Fig. 1^C) and are 25 designed to extend upwardly therefrom on opposite sides of a vertical line extending through the axis of the wheel 114. As these 30 arms are similar in construction a detailed description of one will suffice for both. The arm 115 is provided with a block 116 lapping the upper portion of the periphery of the 35 wheel. The block is provided with a spring pressed latch 117 (Fig. 1^E) for locking the block in adjustable position on the toothed wheel. The block is also provided with a pair of parallel set screws 118 and 119 40 threaded through the block in the plane of the wheel and projecting toward said vertical line through the wheel axis. Preferably the set screws are positioned between the block and a plate 120 (Fig. 1^D) defining 45 its rear face. A screw bolt 121 extends transversely through the block and plate for fastening the screws in place and this bolt may also constitute means for clamping a 50 shouldered periphery of the wheel 114 between split portions 122 of the block (Fig. 1^D).

The inner screws 118 are designed, as they are moved upward and inward by rotary movement in each direction of the wheel 55 114 to engage an arm 123 (Fig. 1^C) the lower end of which is pivoted to the front of the frame 40, and the upper end of which is connected by means of a link 125 to a pivoted arm 124 (Fig. 1^A) at the left of the 60 machine. The lower end of the arm 124 is pivoted to a transverse shaft 126 (Fig. 5^B) which shaft turns the longitudinally extending shaft 127 through meshed bevel gears 128 and 129. The shaft 127 parallels

the lead screw and drives the bevel gear 130 65 slidably keyed thereto. This gear acts through the gear 131 (Fig. 8^A) on the vertically extending shaft 132 to rotate the finger 133 (Fig. 8^B) which constitutes a lateral projection from one side of a hub 134 70 pinned to the upper end of this vertical shaft. The revolving finger works in a notch 135 in the side of the lower member of a transversely extending L-shaped bar 136 fixed to the underside of the transversely movable plate 55. This movement of the finger acts in one direction to throw the plate 55 rearwardly a distance sufficient to permit the tool to clear the work (Fig. 75 6^D) on its reverse traverse. The upper 80 portion of the hub 134 is provided with a sector plate 137 centrally disposed over the finger and constituting a cam for bearing against the side of the upper portion of the L-bar 136.

85 *Mechanism for indexing work.*

A hand lever 138 (Fig. 1^A) is pivoted to a transverse shaft 139 above the wheel 114 and is provided with a lower tail end 140 90 disposed in the path of travel of the upper screws 119. A swinging yoke arm 141 (Figs. 7^A and 10^A) depends from the end of the shaft 139 within the frame of the machine.

The lower end of the lever 141 is rounded and straddles a collar 142 loose on a longitudinally extending reversing actuating rod 143 slidably mounted in the inwardly extending arms 144 of bracket 145 (Fig. 9^A). 100 A pair of spaced apart catch blocks 146 and 147 are pinned to the rod 143 on opposite sides of the collar. A pair of springs 148 and 149 bear respectively on each of the blocks and have their adjacent ends bearing 105 on opposite sides of the collar thereby to form a spring drive between the collar and the rod for movement in either direction. The top face of each block is provided with an outwardly facing shoulder 150 adapted 110 respectively to catch the inwardly facing shoulder 151 on the underside of stop latches 152 and 153. These latches are pivoted to the bracket arms 144 and extend horizontally toward each other. The latches are 115 designed to be raised into unlatched position by fingers 154 projecting laterally from opposite sides of the yoke arm 141 and engaging under the free ends of the latches when the yoke arm approaches the end of its swing. 120

The rod 143 is connected by means of a pivoted link 155 to the upper end of an arm 156 (Fig. 9^B) fixed to a transverse shaft 157 to which shaft is also fastened a bell crank lever 158 one arm of which constitutes an upstanding finger 159. The finger is designed to engage in a notch 160 (Fig. 10^C) on the underside of a horizontally dis-

posed trip lever 161, which lever is pivoted intermediate its length to a sliding clutch member 162. The member is keyed to a main indexing shaft 163 which extends longitudinally of the machine beneath the work table and head stock frame and projects through the right end of the machine. The clutch element is in the form of a sleeve provided with a peripheral groove 164 in which 5 are position rollers 165 journaled in opposite ends of a rocking yoke arm 166 loosely pivoted to the shaft 157. A depending arm 167 of the yoke arm is engaged by a spring 168 acting on the clutch element to move the 10 same into unclutched position. The clutch member is provided with beveled clutch teeth 169 on its outer face designed to engage the teeth of a coacting clutch member 170 loose on the shaft 163. A vertically 15 disposed spring 171 connects the right hand end of the trip lever 161 with a horizontally disposed arm 172 of the bell crank lever 158 to hold the trip lever resiliently in bearing engagement with the top of the finger 159. 20 The clutch member 170 includes a sleeve which extends through the right end of the frame 40 and is provided at its outer end with a worm gear 173 meshing with a worm 25 174 (Fig. 2^A) carried on a transverse shaft 175 mounted on the right end of the machine. A spiral gear 176 is fixed to the shaft 175 and is driven continuously from the spiral gear 63. By this construction the indexing shaft 163 is rotated when the carriage has reached the end of its grinding 30 35 traverse.

The shaft 163 (Fig. 5^B) has a spur gear 177 fixed thereto adjacent its left end (Fig. 3^B) which meshes with a spur gear 178 40 fixed to the outer end of a sleeve 179 journaled in the end of the machine. The gear 178 is of slightly less diameter than the gear 177 so that the gear 177 will not only cause the gear 178 to turn once but will also 45 possess some rotary motion after the indexing mechanism connected thereto has made a complete turn. The inner end of the sleeve is defined by a flat disk 180 constituting one element of a friction clutch drive. The 50 sleeve constitutes a bearing for the outer end of a secondary indexing stud shaft 181 extending to the outside of the machine. A clutch member 182 for coacting with the disk 180 is fixed to the shaft 181 and comprises a drum 183 pinned to the shaft and 55 a flat ring 184 loose on the sleeve 179 and pinned to the drum with the disk positioned therebetween. Leather friction rings 185 are positioned between the faces of the disk 60 and the adjacent faces of the drum and ring. A short clutch controlling shaft 186 is journaled below and parallels the shaft 181. The inner end of this shaft 186 is provided with a tripping arm 187 adapted to be low-

ered from the position shown in Fig. 6^B 65 against the action of spring 187' by means of a pin 188 projecting laterally from the hub of the gear 177. The outer end of the shaft 186 is provided with an arm 189, the outer end of which is defined by a tooth 190 70 designed to lock in the teeth of the gear 191 and in a notch 191' in the drum 183 (Fig. 3^D) to lock the shaft 181 against rotation. A bell-crank lever 192 is mounted 75 loosely on the hub of the arm 189. An upwardly extending arm 193 of this lever constitutes a pawl for engaging a notch 194 in the periphery of the ring 184 to prevent reverse movement of the shaft 181. A spring 195 acts on the other arm 196 of the bell-crank lever to maintain the arm 193 in resilient bearing engagement with the periphery of the ring 184 when in rotation. 80

The gear 191 (Fig. 3^A) is fixed to the outer end of the shaft 181 and constitutes 85 the driving element of a train of gears, the last gear 197 (Fig. 11^B) of which train is fixed to a shaft 198 extending into the frame 41. One, or more intermediate gears 199 of the train are adjustably and de-mountably positioned on a transversely 90 swinging frame 200 (Fig. 3^A) designed to mesh different size gears with the relatively fixed gears 191 and 197.

Mechanism for carrying indexing movement through head stock. 95

The shaft 198 (Fig. 11^B) has a large gear 201 which meshes with a gear 202 constituting part of the right hand member 97 of 100 the differential set loosely mounted on the shaft 92. This member also includes a bevel gear 203 meshing with the bevel gear 95 by means of which the work may be rotated over an angle depending upon the ratio of 105 the gears in the train, 191, 199 and 197.

Mechanism for stopping indexing movements.

A sleeve 204 (Figs. 9^A and 10^A) having a 110 projecting flange 205 defining one end thereof is pinned to the shaft 163 in rear of the left end of the trip lever 161. The sleeve carries a disk 206 (Fig. 9^E) mounted thereon and facing the flange. The flange and disk are resiliently connected by means of a weak spring 207 (Fig. 9^D) housed within a groove 208 (Fig. 9^F) in the adjacent face of the flange. The disk is provided with a finger 209 projecting from its periphery and 115 designed to be rotated by the shaft 163 to bear resiliently on the left-hand side of the trip lever for raising the right end clear of the finger 159 to permit spring 149 to act on rod 143 and thus rotate shaft 157. The 120 sleeve 204 is provided with a pin 210 projecting into the groove 208 just in rear of the spring 207 and a pin 211 projects from 125

the disk 206 into the groove in rear of the pin 210. The pins are so arranged that a positive connection is provided between the sleeve 204 and disk 206 for tripping the lever should the lever resist the resilient action of the spring throw. A yoke arm 212 is fixed to the rear end of the shaft 157 and engages with the clutch element 67 to shift the same to and from the clutch member 67 and 68 depending upon which of the springs 149 or 148 is doing the driving.

Mechanism for adjusting grinding tool.

The grinding tool head 57 includes a pair 15 of upstanding laterally spaced side plates 213 (Fig. 8^A) the front edges of which are outturned and are alined to constitute a guideway for a vertically movable sliding bracket 214 (Figs. 7^A and 7^D). An extension 215 from the upper portion of the bracket projects rearwardly between the plates 213. A vertically extending feed screw 216 has its lower end fixed to the extension and is threaded through a hand 20 wheel 217 mounted in a head bracket 218 constituting the top of the head 57. A circular rim 219 projects forwardly from the front of the bracket 214 (Fig. 7^A) and outlines an opening 220 extending therethrough. A spindle carriage 221 for the grinding wheel spindle 222 (Fig. 2^B) is mounted on said rim for rotary movement about a horizontal axis and has an open back face continuous with the opening 220. 30 The carriage is locked in adjusted position by means of bolts 223 passing through curved slots 224 in the circular base 225 of the carriage and into the front face of the bracket 214. The upper face of the base 225 is provided with a scale 226 (Fig. 7^D) designed to move past the index mark 227 so as to indicate the angular rotation from normal of the grinding tool.

Grinding tool drive.

45 The spindle 222 has a grinding tool, preferably an emery wheel 228 demountably fixed thereto. The wheel is partly housed within and projects from one side of a casing 229 constituting part of the spindle carriage. The spindle is journaled within the casing fixed against end thrusts and has a pulley 230 keyed thereto and driven by means of belt 231, from a pulley 232 (Fig. 7^A) positioned at the rear of the machine. This pulley 232 is driven from some suitable power by means of a belt 233 passed about pulley 234 (Fig. 4^A) fixed to the shaft carrying the pulley 232. The pulleys 232 and 234 (Fig. 3^A) are journaled in a bracket arm 235 pivoted to a rearward extension from the base of the head 57. The belt 231 is stretched under tension by means of a spring 236 which bears on an adjustable 50 nut 237 carried by a rod 238 and on the

arm 235. The rod 238 parallels the run of the belt and has its forward end pivoted to the head 57 (Fig. 4^A).

Manual mechanism for feeding grinding tool. 70

A hand wheel 239 (Fig. 8^B) is fixed to a shaft 240 journaled within a frame 241 extending at an angle forwardly and to the right from the head 57 (Figs. 1^A and 12^B). 75 The inner end of shaft 240 is connected to a vertical shaft 242 through meshed bevel gears 243. A spiral gear 244 fixed to the lower end of shaft 242 meshes with a spiral gear 245 (Fig. 8^C) mounted between a pair 80 of ears 246 depending from the carriage head 57. A transversely disposed feed screw 247 is threaded through the spiral gear 245 and has one end fixed to the forward portion of the plate 55, (Fig. 8^C). The rearward movement of the head 57 may be limited by an adjustable stop 248 projecting from the rear of the plate 55 and this plate may be similarly stopped by means of the stop 249 projecting from the plate 52. 90

Mechanism for finding grinding position.

The hand wheel 239 is provided with a hub 250 (Fig. 8^F) bearing against the end of the frame 241 and has a cone flange rim 95 251 extending from the rear face concentric with the shaft 240. A cone disk 252 is loose upon the hub and is designed to clutch the rim in which position it is held by nut 253 threaded on the hub. A pin 254 projects from the cone disk and is designed to be engaged by a pin 255 extending upwardly from a slide plate 256, adjustable to bring the pin 255 across the path of the pin 254 in which position slide plate is fastened, 100 by nut and slot connection 257, to the top of the frame 241.

Mechanism for adjusting work.

The worm 101 (Fig. 11^B) has an extension 110 258 in the form of a sleeve projecting forwardly through the front of the frame 41 to which extension is fixed a hand wheel 259 held tight against a shoulder 260 on the sleeve by means of a jam nut 261 threaded 115 to the forward end of the extension. The wheel is provided with a centrally disposed cone flange rim 262 engaged by a cone disk 263 keyed to the shaft 100. The cone disk is normally held in frictional engagement 120 with the wheel by a jam nut 264 threaded to the outer end of the shaft 100 and bearing on the disk.

Mechanism for manually feeding tool. 125

The shaft 75 carrying the worm 76 extends forwardly through the right front of the machine and has a large hand wheel 265 (Fig. 7^C) fixed thereto for manually actuating the lead screw 78 thereby to feed the 130

tool carriage manually in its longitudinal traverse.

Adjustment of work in machine.

5 Operation: In operation, the tail stock is slid along the work table and set approximately for the particular length of worm to be ground and is then clamped in place by means of the bolts 46. The work W is 10 centered between the centers 49 and 50, utilizing the centering recesses at the ends of the work remaining from the previous machine operation. The adjusting screw 48 is manipulated until the work is held 15 suspended between the centers with the desired tension after which the clamping screw 51 is tightened up to lock the work against longitudinal movement. The work is rotated by hand about its axis until the same 20 is in position so that both of the flange faces of adjacent threads are engaged by the grinding wheel as shown in Fig. 6c when the wheel is in its set grinding position. This rotary setting of the work is usually 25 by eye, after which the dog screw 110 is tightened onto the work to clamp the same to the face plate 105. The final adjustment so that the grinding wheel will grind exactly 30 the same amount on both sides of the groove is usually made after the grinding wheel has made one or two runs along the worm, by stopping the machine and micrometrically adjusting the centering screws 107 should it be found that the wheel is 35 grinding more on one face than it does on the opposite face.

By means of the mechanism shown in Fig. 11^B an alternative method for making the final adjustment and for indexing the 40 worm by hand is illustrated. The nut 264 may be released slightly, thus freeing the shaft 100 from the worm 101. By manipulating the hand wheel 259, the worm 101 is 45 rotated in either direction independently of the shaft. This rotation of the worm acts through the worm wheel 102 and spindle 103 to the live center 50 and to its dog 109. When the proper rotary adjustment of the 50 work is attained, the nut is tightened up against the cone 263 again locking the shaft 100 to worm 101.

By either of these means the worm may be delicately rotated about its axis into any desired position and securely locked in this 55 adjusted position.

Setting the gear combinations.

The illustrated embodiment of the invention shows the arrangement of the parts 60 when a right-hand-quadruple-threaded worm is being ground. Should it be desired to grind a left-hand-quadruple-threaded worm, the emery wheel head is swung around to the proper angle to bring the 65 working faces of the grinding wheel into

engagement with the worm teeth and an idler gear is either added or subtracted to the gear train formed of the gears 82 to 88 so as to make the worm rotate in the opposite direction while being ground. 70 Should it be desired to grind a worm having a number of teeth different from the four tooth worm shown, a proper size gear wheel is substituted for the gear wheels 83, 84, as is usual in change gear combinations. 75

Adjusting grinding wheel and carriage.

A grinding tool, preferably an emery wheel, particularly designed for the worm to be ground, is mounted on the spindle 222 80 and fastened in place. This emery wheel is trimmed to have a working face fashioned to be the complement of the flank face of the finished worm teeth and where the one grinding wheel is designed to grind opposite faces simultaneously, as in the illustrated machine, the grinding portion of the wheel is provided with a cross-section conforming to the space between the teeth of the finished worm. The emery wheel is then 85 set in its proper grinding position between the threads. Vertical adjustment of the wheel may be attained by rotating the hand wheel 217. An adjustment about a horizontal axis is attained by rotating the spindle carriage 221, the angular movement 90 from normal of which may be ascertained accurately by means of the scale 226. The grinding wheel may be adjusted longitudinally of the work by rotating the hand wheel 265 in one or the other direction. 95 This rotary motion will act through the feed screw 78 to shift the tool carriage and thus cause the working face of the grinding wheel to approach or recede from the adjacent face of the thread. By means of this construction the grinding tool may be raised or lowered, may be advanced or receded from the axis of the worm, may be advanced parallel to the axis and may be 100 revolved about a horizontal axis perpendicular to the axis of the worm.

Setting reversing mechanism.

The arms 115 on the reversing ratchet 115 wheel 114 are adjusted so that the action of the mechanism for moving the tool to and from its grinding engagement with the worm will be inaugurated automatically when the tool carriage has reached the limits of its movement in either longitudinal direction. The screw bolt 121 of one of the blocks 116 is loosened thus permitting the sliding of the block about the periphery of the wheel. The tool carriage is then run 120 manually or mechanically in one direction (longitudinal) until the grinding tool is at the limit of its desired run. The block to be engaged by the arm 123 at this end of the carriage movement is brought up to 125 130

engage the arm. The approximate location of the block for this reversing can be found by placing the latch 117 in the tooth of the wheel which will give the nearest engagement with the arm 123 and the final adjustment is made by rotating the screw 118 into engagement with the arm. The screw 119 is then adjusted to engage the lever at or preferably slightly in advance of the engagement to the screw 118 with the lever 123, after which the screw 121 is tightened thus locking the block in position and clamping the screws against rotation. The carriage is then moved to the other desired 15 limit of its grinding movement and the block and screws of the other reversing arm are adjusted on the wheel as previously described.

Operation for grinding wheel traverse.

Assuming that the different parts are set with the reversing mechanism in the position shown in Fig. 10^A, with the tool carriage at the beginning of its longitudinal 20 traverse and with the sliding plate 55 in its forward position (Fig. 8^C) and the grinding tool in its operative position fitting between the worm threads, or, preferably just back of any possible grinding 25 position, the operator starts the machine by throwing the hand lever 62 and by starting the drive for rotating the grinding tool. Motion is transmitted from the pulley 60 to the bevel gear-coacting-clutch member 69, large bevel wheel 70, gears 73, 30 74, worm 76, worm gear 77, and through the lead screw 78, to the nut 81 attached to the bed plate of the carriage. It will thus be seen that the tool carriage is moved 35 from left to right on its initial grinding 40 traverse.

At the same time the rotation of the lead screw acts through the gear train 82-88, through the left end of the differential set 45 94, through meshed gears 98, 99, through worm 101, spindle 103 to the live center 50 and face plate 105 thereby to rotate the worm W. The ratio of rotary movement 50 of the worm to the advance of the tool carriage may be varied by changing the ratio of gears in the change speed train gear 82-88.

Moving grinding head backward.

As the tool carriage is advancing to the right the ratchet wheel 114 is rotating clockwise due to the rack and gear wheel connection 111 and 112 (Fig. 8^A) and this motion is continued until the screw 118 carried by the left side of the wheel strikes the arm 123 which acts through the link 125 and arm 124 to rotate the chain of shafts 126, 127 and 132 to revolve the finger 133 thereby moving the grinding tool carriage rearwardly out of grinding engagement.

ment with the worm and into the position shown in Figs. 6^D and 12^B. The plate 55 is held to the bed plate 52 by the sector cam plate 137, which engages the foot of the L-bar 136, and at the same time insures an 70 easy throw of the tool carriage.

Operation for disconnecting carriage drive.

At approximately the same time that the screw 118 is set to engage the arm 123, the screw 119 on the advancing block is set to engage the lower end 140 of the lever 138. This movement will cause the lever to swing from the position indicated in Fig. 10^A into the position indicated in Fig. 10^B. As the yoke arm 141 moves the collar 142 to the right, the right hand spring 149 is compressed between the collar and the locked block 147 at the right. When the spring is fully compressed, finger 154 engages the underside of the latch arm 153 to lift the same into the position shown in Fig. 10^B, thus permitting the release of the held block 147 and freeing the compressed spring to drive the rod 143 to the right from the position shown in Fig. 10^A. The springs react through the link 155, arm 156, shaft 157, yoke arm 212 (Fig. 9^B) to shift the sliding clutch element 67 from the position shown in Figs. 10^A and 9^A into 95 the neutral position shown in dotted lines in Fig. 10^B. This will cause the lead screw which has been advancing the tool carriage to be disconnected from the driving shaft 65, thus preventing the further longitudinal 100 traverse of the grinding tool.

Operation of indexing work.

The spring drive of the arm 156 causes the finger 159, which in Fig. 10^A is in the 105 notch 160 on the underside of the trip lever 161, to act therethrough on the sliding clutch member 162, and causes the same to move to the right until the clutch elements 169 and 170 are in their driving engagement. Rotary motion is then transmitted from the main drive gear 64 through worm 174 to the shaft 163 to turn the same. This shaft causes its gear 177 to rotate and thus bring its tripping pin 188 into position to 115 bear on the arm 187 thereby to move the catch 189 out of its normal locking engagement with the teeth of the gear 191 and with the drum 183. This acts to unlock the shaft 181 permitting shaft 163 to drive 120 shaft 181 through the meshed gears 177 and 178 and through the friction clutch provided by the disk 180 running between the leather rings. The shaft 181 acts through the train of gears 191 to 197 to rotate shaft 125 198. This shaft acts through the gears 201 and 202 (Fig. 11^B) to rotate the right hand member of the differential set which in turn act to rotate the shaft 92 and through mesh gears 98 and 99 to rotate the worm 101.

The worm in turn acts through the worm wheel 102 to rotate the live center over an angle depending upon the tooth ratios of the gears in train formed by the gears 191 5 to 197.

Stopping indexing movement.

During the longitudinal movement of the carriage, the shaft 163 is idle and the finger 209 of the shaft locking device is approximately in the position shown in Fig. 9^D. When the shaft has made somewhat less than a complete revolution, the finger 209 will strike down on the left end of the 15 trip lever 161 (Fig. 9^C) causing the right end to swing from the position shown in 10^B into the position shown in Fig. 10^C. The finger is caught by the lever after it has moved from the position shown in Fig. 9^D to 20 the position shown in Fig. 9^C. As the shaft continues to rotate, it expands the spring 207 so that pressure is applied gradually to the lever. If for any reason the spring fails to lower the lever by this resilient connection 25 the pin 211 on the disk sleeve 204 strikes the pin 210 on the disk 206 to force the finger 209 positively into engagement with the lever. The lever is thus raised clear of the finger 159 which permits spring 30 168 to return the clutch member 162 into its normally inoperative position, as shown in Fig. 10^C. Unlatching the trip lever from the shaft 157 permits the spring 149 to expand still further to the right into the position 35 shown in Fig. 10^C. This further spring drive rocks the shaft 157 to swing the clutch sliding element 67 from its neutral position into clutching engagement with the bevel gear co-acting element 68 as shown in dotted lines in Fig. 10^C. The teeth of the clutch members 162 and 170 are beveled on the sides opposite their driving sides so that the sliding clutch member 162 is kicked out of clutching position as soon as the clutch 40 element 170 starts on its reverse movement in case the clutch has not been unlocked by the spring 168.

The spring 207 tends to pull the finger 209 past the lever 161 and into its normal position shown in Fig. 9^C. It will thus be seen that the final movement of the tool carriage is to energize the spring 149 and finally to trip the arm 153 holding the spring. The spring drive first throws the 45 clutch 162 causing the shaft to start on its rotary movement. Then the finger 209 trips the lever 161 disconnecting shaft 163 from its drive at the end of a complete revolution. At the same time the pin 188 has been 50 holding the arm 189 in position unlocked from the gear 191. The length of the arm 189 is so proportioned that the pin will escape therefrom at the end of a complete rotation of the shaft 181 after which the arm

is moved into its shaft locking position by 65 means of its spring. The shaft 181 thus makes one complete revolution at the end of the tool carriage traverse. This revolution of the shaft 181 is reduced by the change speed gear train so that the work is 70 indexed over a definite angle. In the particular embodiment of the invention illustrated the worm turns about 90°. As the gear wheel 177 is slightly larger than gear wheel 178, the shaft 163 is permitted a 75 slight further rotation after the shaft 181 is locked thus insuring the setting of the finger 209.

Having thus particularly described the operation of the mechanism on the grinding traverse of the tool and its movement into its inoperative position, the return of the tool to its position opposite its initial grinding position and its automatic movement toward the worm and into its grinding position will be obvious from the drawings.

In the position shown in Figs. 10^C, 12^A, 12^B and 6^D it will be understood that the rotation of the screw 78 in its reverse direction causes the carriage to be moved longitudinally of the machine back toward the head stock and opposite its initial position. This reverse movement causes the wheel 114 to travel in the direction opposite the direction previously described. The engagement of the screw 118 with the opposite side of the arm 123 shifts the plate 55 forward toward the worm and brings the grinding tool into grinding operation with the threads 100 of the worm. The clutch member 67 is again shifted to repeat the grinding traverse of the tool, and this operation is repeated, the grinding tool traveling repeatedly over its cyclic path moving in grinding 105 relation to the threads of the worm when moving in one direction, then automatically moved out of engagement with the threads, then moved on its inoperative traverse and again moved into operative grinding relation with the threads. This action is repeated, time after time, until the threads are all uniformly ground. As one operator may control several machines it is usual to allow the machines to operate by themselves 115 without any particular attention when once set on their grinding operation. When it is noticed that one of the machines is operating without any grinding engagement between the tool and the worm, the operator advances the grinding tool toward the worm by slightly rotating the hand wheel 229 a distance sufficient to give the grinding member the requisite bite on the worm and the operator then leaves the machine to its 120 own automatic action. This resetting of the grinding tool may be repeated as often as desired, or necessary, and until the proper 125

shape of worm is attained which may be ascertained by means of a suitable gage.

Finding grinding position.

- 5 Should it be desired to move the tool out of its grinding position for any reason as for adjusting the parts, the tool may be accurately returned into its initial position by means of the mechanism illustrated in Fig. 10 8^r. With the tool in its set position, the cone clutch member 252 is loosened and the slide plate 256 is moved forward in its guideway and placed in position with its pin 255 in the path of movement of the pin 254. The 15 cone clutch member 252 is rotated upon the shaft 240 until the pins are in their overlapped engagement, after which the nut 253 is screwed up forcing the clutch member into engagement with the hand wheel 239. The hand wheel may then be rotated 20 in reverse direction moving the pins apart and acting through the shaft 240 to move the grinding tool into an inoperative position clear of the worm threads. When the hand wheel is re-rotated back into position 25 with the pins inter-engaging, the operator is assured that the tool is in the position it was before being displaced. The slide plate is then moved back into an inoperative position 30 and the hand wheel is again free to be rotated at will.

By means of a device of this character it is possible to mount worms of large size in position to be ground and the only necessary movement of the worm is a slow exact rotation of the same about its axis. The floating parts of the machine are carried by the tool carriage which need not be of heavy construction to support the light grinding 35 tool and there is thus attained an economy of power in operating the machine.

Means for providing minute adjustments of both the worm and the grinding tool are included so that the finished worm may be 40 mathematically perfect.

The different operations may be performed manually, or, by the obvious omission of certain driving elements, the operation may be mechanical in some features 45 and manually controlled in other parts. For instance, the traverse of the tool carriage may be automatic while the indexing may be done by hand as where an odd character of worm is to be ground.

50 The operation is in no way controlled by the worm being ground so that inaccuracies in the worm cannot be transferred into the finished product. When once correctly set, the machine may be left to its automatic 55 actuation. The grinding tool moves repeatedly over its path successively engaging one or both of the flange defining succeeding worm grooves. Should the machine run idle 60 no harm would be done as the grinding tool 65 would be merely moving along the grooves.

The operator can tell from the character of sparks from the machine when it is permissible to advance the grinding tool farther into the groove.

When the worm has been ground to 70 proper size, a finishing wheel may be substituted for the grinding wheel and the worm given a finishing polish.

While I have shown and described, and have pointed out in the annexed claims, certain novel features of my invention, it will be understood that various omissions, substitutions, and changes in the form and details of the device illustrated and in its operation may be made by those skilled in the art without departing from the spirit of the invention.

Having thus described my invention, I claim:

1. In a device of the class described, a 85 support, a tool carriage mounted on said support, three superimposed members, the bottom member guided for longitudinal movement along said support, the intermediate member guided for movement transversely of the movement of the bottom member 90 and a top member adjustably mounted on said intermediate member, a bracket slidably mounted for vertical movement on said top member, a tool spindle carriage mounted 95 on the front of said bracket for rotary adjustment about a horizontal axis and a tool spindle mounted for rotary movement in said spindle carriage.

2. In a device of the class described, a 100 support, a tool carriage mounted on said support, three superimposed members, the bottom member guided for longitudinal movement along said support, the intermediate member guided for movement transversely 105 of the movement of the bottom member and a top member adjustably mounted on said intermediate member, a bracket slidably mounted for vertical movement on said top member, a tool spindle carriage mounted on 110 the front of said bracket for rotary adjustment about a horizontal axis, a tool spindle mounted for rotary movement in said spindle carriage, a driving member carried by said top member and a flexible drive between said spindle and driving member.

3. In a device of the class described, a 115 support, a tool carriage mounted on said support, three superimposed members, the bottom member guided for longitudinal 120 movement along said support, the intermediate member guided for movement transversely of the movement of the bottom member and a top member adjustably mounted on said intermediate member, a bracket slidably mounted for vertical movement on said top member, a tool spindle carriage mounted on the front of said bracket for rotary adjustment about a horizontal axis and a tool spindle mounted for rotary movement in 125 130

said spindle carriage and driving means operatively connected to the spindle for driving the same in all of its adjusted positions.

4. In a worm grinding machine, a supporting frame, a head stock fixed thereto and provided with a live center, a tail stock mounted on said frame and provided with a dead center, means for adjusting said centers axially relative to each other, a bed plate carried by said frame, means operatively connected to the live center to rotate the same and to move said plate parallel to a line connecting said centers, said means including an adjustable gear train adapted to be set to cause a predetermined ratio of speed of the plate relative to the speed of rotation of the work carried by said line center, an intermediate plate supported on said bed plate, means for advancing said intermediate plate transversely of the line of movement of the bed plate and a grinding tool supporting member carried by said intermediate plate.
5. In a worm grinding machine, a supporting frame, a head stock fixed thereto and provided with a live center, a tail stock mounted on said frame and provided with a dead center, means for adjusting said centers axially relative to each other, a bed plate carried by said frame, means operatively connected to the live center to rotate the same and to move said plate parallel to a line connecting said centers, an intermediate plate supported on said bed plate, means for advancing said intermediate plate transversely of the line of movement of the bed plate, a grinding tool supporting member carried by said intermediate plate, a grinding tool carried by said supporting member and means for rotating said grinding tool at relatively high speed.
6. In a worm grinding machine, a supporting frame, a head stock fixed thereto and provided with a live center, a tail stock mounted on said frame and provided with a dead center, a bed plate carried by said frame, means operatively connected to the live center to rotate the same and to move said bed plate parallel to a line connecting said centers, an intermediate plate supported on said bed plate, means operable at the end of the bed plate travel for advancing said intermediate plate transversely of the line of movement of the bed plate and a grinding tool supporting member carried by said intermediate plate.
7. In a device of the class described, the combination with a live center and a dead center coactively adapted to hold a worm therebetween, and a tool for grinding the worm, of means operatively connected to the live center to rotate the work about a fixed axis of rotation, automatically actuated means for advancing the tool repeatedly over a cyclic path, one side of which path
- constitutes a straight line parallel to said fixed axis and in position relative thereto so as to bring the tool into operative grinding relation with the worm and other portions of said path being positioned in spaced relation to the axis so as to cause the tool to clear the worm as it moves over said other portions of the path.
8. In a device of the class described, the combination with means for holding and rotating the worm to be ground and a tool for grinding the worm, of means operatively connected to said worm rotating means to rotate the worm about a fixed axis of rotation, means operatively connected to said last named means for advancing the tool repeatedly over a path in position to bring the tool into operative grinding relation to the worm.
9. In a device of the class described, the combination with means for holding the worm to be ground and for rotating the same about its axis, of a grinding tool support, a grinding tool carried by said support, and means engaging the support and acting thereon to advance the tool over a cyclic path, said means including a feed screw operatively connected to the tool support for advancing the tool over a portion of said path.
10. In a device of the class described, the combination with means for holding the worm to be ground and for rotating the same about its axis, of a grinding tool support, a grinding tool carried by said support, and means for advancing the tool in its grinding traverse over a cyclic path, said means including a feed screw operatively connected to the tool support for advancing the tool over a portion of its path parallel to said axis, and said means including mechanism for moving a part of the tool support transversely of said axis at the ends of its grinding traverse.
11. In a device of the class described, a grinding tool support including two superimposed members, a grinding tool controlled in its bodily movement by said two members, a feed screw operatively connected to one of said members for moving the tool over paths parallel to each other, mechanism operatively connected to the other member for moving the tool over paths parallel to each other but at an angle to said first named paths and means operatively controlled by the position of the tool support for moving the tool from one path into one of the paths angularly disposed relative thereto whereby said tool will describe a cyclic movement over said paths.
12. In a worm grinding machine, the combination with means for rotating the worm about its axis, of a grinding tool support operatively controlling the move of said support whereby the tool carried thereby

will be given a bodily movement over a substantially rectangular cyclic path, one side of said path being parallel to the axis of rotation of the worm and the adjacent 5 sides being substantially at right angles to said axis, said mechanism including means operatively engaging said tool support, for changing the direction of movement of the same at the end of its travel in each direction.

10 13. In a device of the class described, the combination of means for holding a worm in position to be ground, a grinding tool guided for grinding movement parallel to the axis of the worm, automatically actuated 15 means for moving the tool into an inoperative position at the end of its grinding movement and means for returning the tool, while in its inoperative position to the beginning of its grinding position.

20 14. In a machine for grinding the teeth of worms, the combination with means for holding a worm in position to be ground, of a rotary grinding tool, means for rotating said tool, means for moving said tool parallel 25 to the axis of the worm and means for moving the tool at right angles to said axis, said second named means automatically operable at the end of a predetermined movement of the tool under the action of 30 said first named means.

15 15. In a worm grinding machine, the combination with means for supporting and rotating the worm to be ground, of a rotating grinding tool, a tool carriage for supporting 35 the grinding tool, a feed screw for advancing said carriage with the grinding tool in operative relation to the worm to be ground and mechanism for automatically moving the tool into an inoperative position relative 40 to the worm at the end of the grinding movement.

16. In a worm grinding machine, the combination with means for supporting and rotating the worm to be ground, of a rotating 45 grinding tool, a tool carriage for supporting the grinding tool, a feed screw for advancing said carriage with the grinding tool in operative relation to the worm to be ground, mechanism operating on the carriage for 50 automatically moving the tool into an inoperative position relative to the worm at the end of the grinding movement, and means operatively connected to the worm rotating means and to the feed screw for 55 simultaneously reversing the direction of rotation of the same while the tool is in its inoperative position.

17. In a worm grinding machine, the combination with means for supporting and rotating the worm to be ground, of a grinding tool, a tool carriage for supporting the grinding tool, a feed screw for advancing said carriage with the grinding tool in operative relation to the worm to be 65 ground, mechanism operating on the car-

riage for moving the tool into an inoperative position relative to the worm at the end of the grinding movement, means operatively connected to the worm rotating means and to the feed screw for reversing the direction 70 of rotation of the same while the tool is in its inoperative position.

18. In a worm grinding machine, the combination of a grinding tool, a tool carriage for supporting the grinding tool, a feed screw for advancing said carriage with the grinding tool in one direction, mechanism continuously connected to the carriage and operating thereon for automatically moving the tool into an inoperative position at the 80 end of the movement in said direction, means operatively connected to the feed screw for reversing the direction of rotation of the same while the tool is in its inoperative position and means controlling said 85 mechanism for reversing the actuation of the same when the tool has arrived opposite its initial grinding position thereby to move the tool into its operative grinding position.

19. In a worm grinding machine, the combination with means for rotating the worm about its axis, of a grinding tool, mechanism operatively controlling said tool whereby the tool will be given a bodily movement over a substantially rectangular cyclic path, 95 one side of said path being parallel to the axis of rotation of the worm and the adjacent sides being substantially at right angles to said axis, said mechanism including means operatively engaging said tool for 100 changing the direction of movement of the same at the end of its travel in each direction and adjustable means controlling said mechanism for varying the dimensions of 105 said path of travel.

20. In a worm grinding machine, the combination with means for rotating the worm about its axis, of a grinding tool, mechanism operatively controlling said tool whereby the tool will be given a bodily 110 movement over a substantially rectangular cyclic path, two sides of said path being parallel to the axis of rotation of the worm and the adjacent sides being substantially at right angles to said axis, said mechanism 115 including means operatively engaging said tool for changing the direction of movement of the same at the end of its travel in each direction, said last named means operatively connected to the means for rotating the 120 worm for reversing the direction of rotation of the worm as the tool enters and leaves the sides of the path paralleling the axis of the worm.

21. In a device of the class described, the 125 combination with means for rotatably supporting a worm to be ground, of a grinding tool carriage, a grinding tool mounted in said carriage in position to grind the worm, a lead screw engaging said carriage to move 130

- the tool parallel to the axis of the worm, a drive for said lead screw, a main drive, a two position clutch, said clutch in one position connecting the main drive and the lead screw drive to rotate the screw clockwise and in the other position to rotate the screw anticlockwise, a driving connection between said lead screw and the means supporting the worm thereby to rotate the worm with the screw and means for changing said driving connection thereby to change the ratio of said screw turn to the worm turn. 70
22. In a device of the class described, the combination with means for rotatably supporting a worm to be ground, of a grinding tool carriage, a grinding tool mounted in said carriage in position to grind the worm, a lead screw engaging said carriage to move the tool parallel to the axis of the worm, a drive for said lead screw, a main drive, a two position-clutch, said clutch in one position connecting the main drive and the lead screw drive to rotate the screw clockwise and in the other position to rotate the screw anticlockwise, said last named means being adjustable whereby the lead screw action may be reversed at different positions of the carriage traverse. 75
23. In a device of the class described, the combination with means for rotatably supporting a worm to be ground, of a grinding tool carriage, a grinding tool mounted in said carriage in position to grind the worm, a lead screw engaging said carriage to move the tool parallel to the axis of the worm, a main drive, a two position clutch, said clutch in one position connecting the main drive and the lead screw to rotate the screw clockwise and in the other position to rotate the screw anticlockwise, said last named means being adjustable whereby the lead screw action may be reversed at different positions of the carriage traverse. 80
24. In a device of the class described, the combination with means for rotatably supporting a worm to be ground, of a grinding tool carriage, a grinding tool mounted in said carriage in position to grind the worm, a lead screw engaging said carriage to move the tool parallel to the axis of the worm, a main drive, a two position clutch, said clutch in one position connecting the main drive and the lead screw to rotate the screw clockwise and in the other position to rotate the screw anticlockwise, said last named means being adjustable whereby the lead screw action may be reversed at different positions of the carriage traverse. 85
25. In a worm grinding machine, a support provided with a dead center and a live center coaxially adapted to hold a worm therebetween, a tool carriage, means for guiding the carriage on said support parallel to the axis of the worm between the centers, means acting on the live center for rotating the work, means acting on the carriage for advancing the same longitudinally along its guiding means for a preset distance and a driving mechanism for actuating both of said last named means. 90
26. In a worm grinding machine, the combination with means for supporting and rotating the worm to be ground, of a grinding tool, a tool carriage for supporting the grinding tool, a feed screw for advancing said carriage with the grinding tool in operative relation to the worm to be ground, means operatively connected to the worm rotating means and to the feed screw for reversing the direction of rotation of the same and means controlling said mechanism for reversing the actuation of the same when the tool has arrived opposite its initial grinding position. 95
27. In a device of the class described, the combination with means for rotatably supporting a worm to be ground, of a grinding tool carriage, a grinding tool mounted in said carriage in position to grind the worm, a lead screw engaging said carriage to move the tool parallel to the axis of the worm, a main drive, a two position clutch, said clutch in one position connecting the main drive and the lead screw to rotate the screw clockwise and in the other position to rotate the screw anticlockwise and a driving connection between said lead screw and the means supporting the worm thereby to rotate the worm with the screw. 100
28. In a device of the class described, the combination with means for rotatably supporting a worm to be ground, of a grinding tool carriage, a grinding tool mounted in said carriage in position to grind the worm, a lead screw engaging said carriage to move the tool parallel to the axis of the worm, means for driving the screw first in one direction and then in the reverse direction, a train of gears connecting said lead screw and said worm supporting means whereby the worm will turn in unison with the screw and mechanism dependent upon the number of turns of the lead screw in one direction for reversing the direction of drive of the screw and worm. 105
29. In a device of the class described, the combination with means for rotatably supporting a worm to be ground, of a grinding tool carriage, a grinding tool mounted in said carriage in position to grind the worm, means operating on the carriage for feeding the tool in its grinding traverse along the worm, means for rotating the worm, a change-speed connection between said last named means, and a single drive for both of said means. 110
30. In a machine for grinding worms, the 115
5. lead screw to rotate the screw clockwise and in the other position to rotate the screw anticlockwise and means automatically operated by the carriage at the end of its movement for throwing the clutch from one position into the other. 120
10. worm to be ground, of a grinding tool carriage, a grinding tool mounted in said carriage in position to grind the worm, a lead screw engaging said carriage to move the tool parallel to the axis of the worm, a main drive, a two position clutch, said clutch in one position connecting the main drive and the lead screw drive to rotate the screw clockwise and in the other position to rotate the screw anticlockwise, said last named means being adjustable whereby the lead screw action may be reversed at different positions of the carriage traverse. 125
15. worm to be ground, of a grinding tool carriage, a grinding tool mounted in said carriage in position to grind the worm, a lead screw engaging said carriage to move the tool parallel to the axis of the worm, a main drive, a two position clutch, said clutch in one position connecting the main drive and the lead screw to rotate the screw clockwise and in the other position to rotate the screw anticlockwise, said last named means being adjustable whereby the lead screw action may be reversed at different positions of the carriage traverse. 130

- combination with means for supporting and rotating the worm, of a grinding tool carriage, a tool supported from said carriage and adapted to be moved thereby into grinding relation with the worm in a direction along the axis thereof, means for feeding the carriage in said direction, a reversing wheel, a driving connection between said carriage and wheel, an actuating member 5 adjustable about the periphery of said wheel, a control disposed in the path of movement of said actuating member and means governed by said control for reversing the operation of said carriage feeding means.
- 15 31. In a machine for grinding worms, the combination with means for supporting and rotating the worm, of a grinding tool carriage, a tool supported from said carriage and adapted to be moved thereby into grinding 20 relation with the worm in a direction along the axis thereof, means for feeding the carriage in said direction, a reversing wheel, a driving connection between said carriage and wheel, an actuating member adjustable about the periphery of said wheel, a control disposed in the path of movement of said actuating member, means governed by said control for reversing the operation of said carriage feeding means and another 25 actuating member adjustable about the periphery of said wheel adapted to actuate said control in its opposite direction for again reversing the operation of said carriage feeding means to bring the tool into its worm 30 grinding position.
32. In a machine for grinding worms, the combination with means for supporting and rotating the worm, of a grinding tool carriage, a tool supported from said carriage and adapted to be moved thereby into 35 grinding relation with the worm in a direction along the axis thereof, means for feeding the carriage in said direction, a reversing wheel, a driving connection between said carriage and wheel and means carried by the reversing wheel for reversing the operation of said carriage feeding means.
- 40 33. In a worm grinding machine, the combination with means for rotating the worm about its axis, of a grinding tool, means for feeding the tool axially along the worm while the same is rotating, mechanism operatively connected to the tool for moving the same at an angle to said worm axis 45 to and from a grinding engagement with the worm, means for inaugurating the operation of said mechanism, said inaugurating means being adjustable whereby the tool may be moved automatically relative to the 50 axis of the worm at a preset place along the length of the worm.
- 55 34. In a worm grinding machine, the combination with means for rotating the worm about its axis, of a grinding tool, means for feeding the tool axially along the 60 worm while the same is rotating, mechanism operatively connected to the tool for moving the same at an angle to said worm axis to and from a grinding engagement with the worm, means for inaugurating the operation of said mechanism.
- 65 35. In a worm grinding machine, the combination with means for rotating the worm about its axis, of a grinding tool, means for feeding the tool axially along the worm while the same is rotating, mechanism operatively connected to the tool for moving the same at an angle to said worm axis to and from a grinding engagement with the worm, means for inaugurating the operation of said mechanism.
- 70 36. In a device of the class described, the combination with means for holding the worm to be ground and a tool carriage, a grinding tool supported by the carriage and means for moving said carriage longitudinally, of means for moving the tool transversely to and from the worm holding means, said means including a shiftable element constituting part of the carriage, said 75 element provided with a notch in the side thereof, a rotatably mounted finger engaging said notch to shift the element and means for rotating said finger.
- 80 37. In a device of the class described, the combination with means for holding the worm to be ground and a tool carriage, a grinding tool supported by the carriage and means for moving said carriage longitudinally, of means for moving the tool transversely to and from the worm holding means, said means including a shiftable element constituting part of the carriage, and rapidly actuated means engaging said shiftable element to throw the same quickly into 85 a position to remove the grinding tool from its grinding position.
- 90 38. In a device of the class described, the combination with means for holding the worm to be ground and a tool carriage, a grinding tool supported by the carriage and means for moving said carriage longitudinally, of means for moving the tool transversely to and from the worm holding means, said means including a shiftable element constituting part of the carriage, means for guiding said element in a direction to cause the grinding tool to clear the sides of the threads when withdrawn from its grinding engagement therewith, and 95 means for moving the element along said grinding means.
- 100 39. In a device of the class described, the combination with means for supporting the worm to be ground, a tool for grinding the worm, a carriage for said tool, means for moving the carriage bodily along the length of the worm, said carriage including an element for moving the tool transversely 105 of the length of the worm, a vertically ex-

- tending shaft, means carried by said shaft and engaging said element to shift the same, a revolving arm operatively connected to the carriage to be moved thereby and means disposed in the path of movement of said revolving arm and operatively connected to said vertical shaft whereby said element is shifted when the movement of the carriage causes said arm to engage 10 said last named means.
40. In a machine for grinding worms, the combination of a grinding medium having its working face of a contour complementary to the flange face of the worm thread to be ground, means for supporting the worm to be ground, mechanism for bringing the working face of the grinding medium into operative engagement with the flange face of the worm thread and means for indexing 15 said worm after each thread is ground thereby to present another thread in proper position to be engaged by the grinding medium.
41. In a machine for grinding worms, the combination of a rotating grinding wheel having its working face of a contour complementary to the flange face of the worm thread to be ground, means for rotating said wheel at relatively high speed, means 20 for supporting the worm to be ground, mechanism for bringing the working face of the grinding wheel into operative engagement with the flange face of the worm thread along the length of the same and means for automatically indexing said worm after each thread is ground thereby to present another thread to the operation 25 of the grinding wheel.
42. The combination in an organized machine for grinding worms, of a rotary worm holder, means for rotating said holder continuously during the grinding operation, an indexing mechanism operatively connected to the holder to rotate the same, a rotary 30 grinder fashioned to have a cross-section designed to fit the space between adjacent threads of the finished worm and means co-acting with the indexing mechanism for bringing the grinder into operative engagement successively with the different threads.
43. In a worm grinding machine, the combination with means for supporting and rotating the worm during the grinding operation, means operatively connected to said 35 first named means for indexing the worm, a grinding tool, a carriage for advancing said tool in grinding relation to said rotating work and means controlled by the movement of the carriage into a preset position 40 for inaugurating the actuation of said indexing means.
44. In a worm grinding machine, an indexing mechanism including means for supporting and rotating the worm during the 45 grinding operation, a shaft, means for ro-
- tating said shaft over one complete turn at a time, and a train of gears connecting said shaft and said worm rotating means whereby the single rotation of said shaft will cause said worm to be indexed over an angle 50 dependent upon the gears in the gear train.
45. In a worm grinding machine including a traveling grinding tool support, an indexing mechanism including means for supporting and rotating the worm to be ground, 55 a shaft, means controlled by the movement of the support into a preset position for rotating said shaft over one complete turn at a time, and a train of gears connecting said shaft and said worm rotating means 60 whereby the single rotation of said shaft will cause said worm to be indexed over an angle dependent upon the gears in the gear train.
46. In a worm grinding machine, an indexing mechanism including means for holding and rotating the worm, a continuously 65 rotating main drive, a shaft, means for limiting the angular rotation of said shaft over a definite angle, a clutch for connecting said drive and shaft, means controlling the clutch for coupling said shaft with the main drive thereby to rotate the shaft over its definite angle of rotation and a change speed gear combination between said shaft 70 and said worm rotating means.
47. In a worm grinding machine, an indexing mechanism including means for holding and rotating the worm, a continuously 75 rotating main drive, a shaft, a clutch 80 for connecting said drive and shaft, means controlling the clutch for coupling said shaft with the main drive to rotate the shaft over a definite angle of rotation and a driving connection between said shaft and said 85 worm rotating means.
48. In a worm grinding machine, an indexing mechanism including a worm rotating means, a shaft operatively connected thereto, a driving element, a clutch for connecting said shaft and driving element, a spring 90 acting on said clutch normally holding the same in unclutched position, a spring drive connected to said clutch for moving in one direction against the action of said 95 spring, first into a locked inoperative position and then into a clutching position.
49. In a worm grinding machine, an indexing mechanism including a worm rotating means, a shaft operatively connected 100 thereto, a driving element, a clutch for connecting said element with said shaft to rotate the same, a spring drive for moving said clutch into operative position, means acting on said spring for placing the same 105 under tension and means for delaying the action of said spring until compressed to the desired tension.
50. In a worm grinding machine, an indexing mechanism including a worm rotat- 110

ing means, a shaft operatively connected thereto, a driving member, a clutch element slidably mounted on said shaft, for connecting said driving member and said shaft, a 5 tripping lever pivoted to said clutch element, a shaft extending transversely of said first named shaft, an actuating lever fixed to said traverse shaft and adapted to engage said tripping lever to shift the clutch member, 10 a spring pressed rod connected to said actuating lever for moving the same and means operatively connected to said rod to actuate the same.

51. In a worm grinding machine, an indexing mechanism including a worm rotating means, a shaft operatively connected thereto, a driving member, a clutch element slidably mounted on said shaft, for connecting said driving member and said shaft, a 20 tripping lever pivoted to said clutch element, a shaft extending transversely of said first named shaft, an actuating lever fixed to said traverse shaft and adapted to engage said tripping lever to shift the clutch member, a 25 spring pressed rod connected to said actuating lever for moving the same, means operatively connected to said rod to actuate the same, means for rotating said worm rotating means and a clutch controlled by said traverse shaft for actuating said last named means.

52. In a device of the class described, mechanism for indexing the worm, including a main shaft, means for rotating the 35 shaft over a definite angle, a second shaft, a driving connection between said shafts, means engaging the driving connection for locking said second shaft against rotation, a worm supporting and rotating mechanism, 40 a change gear connection between said second shaft and said mechanism and means operated by the rotation of said first shaft and engaging said locking means to move the same into inoperative position and thus 45 permit the actuation of said second shaft.

53. In a device of the class described, mechanism for indexing the worm, including means for supporting and rotating the worm, a driving shaft, means for rotating 50 the shaft over a definite angle and a change gear connection between said shaft and said worm rotating means.

54. In a device of the class described, mechanism for indexing the worm, including means for supporting and rotating the worm, a driving shaft, means for rotating the shaft over a definite angle and a change gear connection between said shaft and said 55 worm rotating means and means acting directly on said worm rotating means for turning the same while being ground.

55. In a worm grinding machine, the combination of means for holding and rotating the worm, a grinding tool, a carriage for 60 moving the tool in grinding relation to the

worm, an indexing mechanism operatively connected to the worm rotating means to index the worm and a main drive operatively connected to said carriage, a driving connection between said main drive and 70 said indexing mechanism, said driving connection operatively controlled by the position of said carriage.

56. In a worm grinding machine, the combination of means for holding and rotating 75 the worm, a grinding tool, a carriage for moving the tool in grinding relation to the worm, an indexing mechanism operatively connected to the worm rotating means to index the worm, a main drive operatively 80 connected to said carriage, a driving connection between said main drive and said indexing mechanism, said driving connection operatively controlled by the position of said carriage and means for varying the direction of travel of the carriage relative to 85 the direction of rotation of the indexing mechanism.

57. In a worm grinding machine, the combination of means for holding and rotating 90 the worm, a grinding tool, a carriage for moving the tool in grinding relation to the worm, an indexing mechanism operatively connected to the worm rotating means to index the worm, and means operatively actuated by said carriage for actuating said indexing mechanism. 95

58. In a worm grinding machine, an indexing mechanism including means for rotating the worm, a driven shaft operatively 100 connected thereto, a friction clutch element fixed to said shaft, a coacting friction clutch element loose on said shaft but in frictional driving engagement therewith through the coacting clutch elements, a driving shaft in 105 driving engagement with said loosely mounted clutch element, a braking device normally holding said driven shaft against rotation and a tripping device actuated by the driving shaft and acting on said braking device to move the same into an inoperative position. 110

59. In a worm grinding machine, the combination of a driven shaft, an indexing mechanism operatively connected to said 115 shaft, a driving shaft, a controlling clutch for connecting said shafts, means for moving said clutch into operative position and means carried by the driven shaft for moving said clutch into an inoperative position 120 at the end of a complete rotation of said driven shaft.

60. In a worm grinding machine, the combination of an indexing mechanism, a shaft for actuating said mechanism, a driving 125 member, means for connecting said shaft and driving member and means controlled by the rotary movement of said shaft over a definite angle for disconnecting said shaft and driving member.

61. In a worm grinding machine, the combination with an indexing mechanism including a shaft, of a driving member, a clutch for connecting said shaft and driving member, means for moving said clutch into an operative position, means for locking said clutch in position and means controlled by the rotary movement of the shaft for moving said locking means into an inoperative position.
62. In a worm grinding machine, the combination with an indexing mechanism including a shaft, of a driving member, a clutch for connecting said shaft and driving member, means for moving said clutch into an operative position, means for locking said clutch in position, means controlled by the rotary movement of the shaft for moving said locking means into an inoperative position and means for moving said unlocked clutch into an inoperative position at the end of said rotary movement of the shaft.
63. In a worm grinding machine, the combination with an indexing mechanism including a shaft, of a driving member, a clutch for connecting said shaft and driving member, means including a tripping lever for moving said clutch into operative position, a finger carried by said shaft and adapted to be rotated thereby to engage said tripping lever and means controlled by the lever for moving said clutch into inoperative position.
- 35 64. In a worm grinding machine, the combination with an indexing mechanism including a shaft, of a driving member, a clutch for connecting said shaft and driving member, means including a tripping lever for moving said clutch into operative position, a finger carried by said shaft and loosely mounted thereon, a spring connecting said finger and shaft and adapted to be rotated thereby to engage said tripping lever and means controlled by the lever for moving said clutch into inoperative position.
- 40 65. In a worm grinding machine, the combination with an indexing mechanism including a shaft, of a driving member, a clutch for connecting said shaft and driving member, means including a tripping lever for moving said clutch into operative position, a finger carried by said shaft and loosely mounted thereon, a spring connecting said finger and shaft and adapted to be rotated thereby to engage said tripping lever, means controlled by the lever for moving said clutch into inoperative position and means for positively connecting said finger and shaft thereby to actuate the lever.
- 45 66. In a worm grinding machine, the combination with a movable grinding tool carriage and an indexing mechanism, of a driving member for the indexing mechanism, means controlled by the moving carriage for connecting said mechanism and driving member and means controlled by the indexing mechanism for disconnecting the mechanism from its driving member.
67. In a worm grinding machine, an indexing mechanism including a shaft, a worm support geared to said shaft, a continuous drive loose on said shaft and fixed against longitudinal movement thereon, a driving clutch element driven from said drive, a driven clutch element slidably keyed to said shaft, a spring engaging said sliding element for moving the same into unclutched position, means for moving said sliding element into engagement with the relatively fixed element, thereby to drive the shaft and for placing said spring under tension, means for locking said sliding clutch element in its clutching position and means for moving said locking means into inoperative position and thus permit the actuation of the spring.
- 70 68. In a worm grinding machine, an indexing mechanism including a shaft, a work support geared to said shaft, a continuous drive loose on said shaft and fixed against longitudinal movement thereon, a driving clutch element driven from said drive, a driven clutch element slidably keyed to said shaft, a spring engaging said sliding element for moving the same into unclutched position, means for moving said sliding element into engagement with the relatively fixed element, thereby to drive the shaft, and for placing said spring under tension, means for locking said sliding clutch element in its clutching position and means carried by the shaft adapted to engage said locking means at the end of a rotary movement of the shaft over a preset angle thereby to move the locking means into inoperative position and thus permit the actuation of the spring.
- 75 69. In a worm grinding machine, an indexing mechanism including a shaft, a work-supporting and turning means, a change gear connection between said shaft and turning means, means for rotating the shaft, means controlling said last named means for inaugurating the rotation of the indexing movement of said mechanism and means carried by the shaft for stopping the indexing movement after the work has been turned over a definite angle.
- 80 70. In a worm grinding machine, an indexing mechanism including a main shaft, a secondary shaft, a friction clutch between the shafts, a work rotating means operatively connected to said supplemental shaft, means for rotating said main shaft, a clutch for connecting said rotating means and said main shaft, means carried by the main shaft for moving said clutch into inoperative po-
- 85 90 95 100 105 110 115 120 125 130

sition approximately at the end of a complete revolution of the shaft and means co-acting with said friction clutch to limit the rotary movement of the supplemental shaft 5 to 360°.

71. In a worm grinding machine, an indexing mechanism including means for rotating the worm, and drive for said means, said drive including two shafts, one a driven shaft connected to said worm rotating means and the other a driving shaft designed to drive said driven shaft, means providing a slipping action between said shafts when operatively connected, means 10 acting on the supplemental shaft limiting its rotary movement to 360°, means acting on said main shaft limiting its rotary movement to 360° and a slightly multiplying gear connection between said shafts where- 15 20 by said main shaft has a slight further rotary movement after the secondary shaft has stopped.

72. In a worm grinding machine, an indexing mechanism including means for rotating the worm, and drive for said means, said drive including two shafts, one a driven shaft connected to said worm rotating means and the other a driving shaft designed to drive said driven shaft, means 25 providing a slipping action between said shafts when operatively connected, means acting on the supplemental shaft limiting its rotary movement to 360°, means acting on said main shaft limiting its rotary movement to 360°, a slightly multiplying gear connection between said shafts whereby said main shaft has a slight further rotary movement after the secondary shaft has stopped, means for connecting a driving 30 mechanism to said main shaft, and means actuated by said further rotary movement of said main shaft and acting on said connecting means for disconnecting said driving mechanism from its driving engagement with said main shaft. 35 40 45

73. In a worm grinding machine, an indexing mechanism including means for rotating the worm, a driven shaft operatively connected thereto, a driving shaft, a clutching member, a relatively large gear carried by the driving shaft, a relatively small gear carried by the clutching member and meshing with said large gear, and a slipping clutch connecting said clutching member 50 and said driven shaft.

74. In a worm grinding machine, an indexing mechanism including means for rotating the worm, and drive for said means, said drive including two shafts, one a driven shaft connected to said worm rotating means and the other a driving shaft designed to drive said driven shaft, means providing a slipping action between said shafts when operatively connected, means acting on the 55 60 65 70 75 80 85 90 95 100 105 110 115 120 125

supplemental shaft limiting its rotary move- 65 ment to 360°, means acting on said main shaft limiting its rotary movement to 360°, a slightly multiplying gear connection between said shafts whereby said main shaft has a slight further rotary movement after 70 the secondary shaft has stopped, means for connecting a driving mechanism to said main shaft, means actuated by said further rotary movement of said main shaft and acting on said connecting means for disconnecting said driving mechanism from its driving engagement with said main shaft, means normally bearing on said driven shaft for breaking the same and a tripping means operated by the rotation of the driving shaft 80 for releasing said breaking means thereby to permit the driving shaft to rotate the driven shaft.

75. In a worm grinding machine, an indexing mechanism including means for rotating the worm and drive for said means, said drive including two shafts, one a driven shaft connected to said worm rotating means and the other a driving shaft designed to drive said driven shaft, means providing a slipping action between said shafts when operatively connected, means acting on the supplemental shaft limiting its rotary movement to 360°, means acting on said main shaft limiting its rotary movement to 360°, a slightly multiplying gear connection between said shafts whereby said main shaft has a slight further rotary movement after the secondary shaft has stopped, means for connecting a driving mechanism to said 100 main shaft, means actuated by said further rotary movement of said main shaft and acting on said connecting means for disconnecting said driving mechanism from its driving engagement with said main shaft, means normally bearing on said driven shaft for breaking the same, a tripping means operated by the rotation of the driving shaft for releasing said breaking means thereby to permit the driving shaft to rotate the driven shaft and means carried by the driven shaft for limiting its rotary movement. 105 110 115 120 125

76. In a machine for grinding worms, the combination of a live center and a dead center adapted to hold the worm therebetween in fixed position, means for rotating the held worm about its axis, a grinding tool adapted to be set in grinding position between the threads of the worm, adjusting means engaging the worm to rotate the same slightly about its axis of rotation into position whereby the grinding tool will be caused to have a grinding fit with one of the worm teeth. 120 125

77. In a machine for grinding worms, the combination of a live center and a dead center adapted to hold the worm therebe-

tween and to rotate the same about its axis, a grinding tool adapted to be set in grinding position between the threads of the worm, a face plate rotating with said live center, a 5 dog adapted to be clamped to the worm and provided with a tail facing said face plate and means carried by the face plate and engaging said tail to shift the worm about its axis thereby to permit the advance of the 10 grinding tool into grinding engagement with the teeth of the worm.

78. In a worm grinding machine, the combination with means for supporting and rotating the worm to be ground, a grinding 15 wheel adjustable in a right line to and from the axis of rotation of the worm into position to grind the sides of the threads thereof, means for rotating the grinding wheel and means for displacing the wheel axially 20 of the worm and manually actuated means for operating said last named displacing means.

79. In a worm grinding machine, the combination with means for holding the worm 25 to be ground, of a rotary grinding tool adapted to be placed in position relative to said worm to grind the faces of the threads thereof, a carriage for said tool, said carriage including a bed plate mounted for 30 movement longitudinally of the axis of the worm when in position in the machine, an intermediate plate carried by said bed plate and guided for movement thereon transversely of said axis, a tool supporting head 35 carried by said intermediate plate, a grinding tool mounted for rotary movement in said head, means for rotating the tool, means for moving said bed plate, means for moving said intermediate plate and manually 40 actuated means for adjusting the position of said intermediate plate on said bed plate.

80. In a worm grinding machine, a rotary 45 grinding tool, a carriage therefor, means acting on said carriage for moving the tool in one direction and means for moving the tool in a direction at right angles to said first named direction, mechanically driven mechanism adapted to be coupled with both of said means to actuate the same, and manually 50 actuated mechanism adapted to be coupled with both of said means to actuate the same.

81. In a device of the class described, a support, a tool carriage mounted on said 55 support, and including three superimposed members, the bottom member guided for longitudinal movement along said support, the intermediate member guided for movement transversely of the movement of the bottom member, a top member adjustably mounted on said intermediate member, a bracket slidably mounted for vertical movement on said top member, a tool spindle case mounted on the front of said bracket

for rotary adjustment about a horizontal 65 axis, a tool spindle mounted for rotary movement in said spindle casing and manually actuated means operatively connected to said members for adjusting the positions of the same relative to each other. 70

82. In a worm grinding machine, the combination with means for rotating the worm about its axis, of a grinding tool, means for feeding the tool axially along the worm while the same is rotating, mechanism operatively connected to the tool for moving the same at an angle to said worm axis to and from a grinding engagement with the worm and manually controlled means operatively connected to said mechanism for 80 adjusting the grinding position of the tool.

83. In a device of the class described, the combination with a grinding tool carrying member, a grinding tool carried thereby, manually actuated means engaging said member for advancing the tool to and from its grinding position and means for identifying a preset position of the tool, said means including a stop adapted to be fixed to said manually actuated means and another stop adapted to be fixed in position in the path of advance of said first named stop. 85

84. In a device of the class described, a mechanism for resetting a revolving member in a preset position, a member normally loose on said revolving member, means for temporarily fastening said loose member to said revolving member, said loose member provided with a pin projecting therefrom parallel to the axis of rotation of 100 the revolving member and a stop member adapted to be moved into position in the path of revolution of said pin to limit the movement of said rotary member. 95

85. In an organized worm grinding machine, the combination with means for holding the worm to be ground and a grinding tool for grinding the flange faces of the worm teeth, of means for advancing the tool into and from grinding engagement 105 with the worm and mechanism adapted to be operatively connected to said means for locating a grinding position of the tool whereby said tool may be returned exactly to said located position after it has been 110 moved from said position. 115

86. In an organized worm grinding machine, the combination with means for holding the worm to be ground, and a grinding tool for grinding the teeth of the worm, of means including a free rotary member for advancing the tool to and from grinding engagement with the worm, a stop mounted for revolving movement about the axis of said rotary member, a fixed stop adapted 120 to have said revolute stop contact therewith, means for fastening said revolute stop to said rotary member, said rotary 125

member with stop fastened thereto and adapted to be revolved away from said fixed stop.

87. In a machine for grinding worms, the combination of means for revolving the worm about its axis at a predetermined speed, a grinding wheel and means for revolving the same, means for feeding the grinding wheel along the worm and in grinding contact therewith at a speed having a predetermined relation to the speed of revolution of the worm, means for automatically withdrawing the grinding wheel from the worm at one end of its travel and for automatically returning it into grinding position at the other end of its travel, and means for automatically reversing the direction of travel of the grinding wheel at predetermined limits.

88. In a machine for grinding worms, the combination of means for revolving the worm about its axis at a predetermined speed, a grinding wheel and means for revolving the same, means for feeding the grinding wheel along the worm and in grinding contact therewith at a speed having a predetermined relation to the speed of revolution of the worm, means for automatically withdrawing the grinding wheel from the worm at one end of its travel and for automatically returning it into grinding position at the other end of its travel, and means for automatically reversing the direction of travel of the grinding wheel at predetermined limits and means for automatically indexing the worm while the grinding tool is out of grinding contact with the worm.

89. In a machine for grinding worms, the combination of means for revolving the worm about its axis at a predetermined speed, a grinding wheel and means for revolving the same, means for feeding the grinding wheel along the worm and in grinding contact therewith at a speed having a predetermined relation to the speed of revolution of the worm, means for automatically withdrawing the grinding wheel from the worm at one end of its travel and for automatically returning it into grinding position at the other end of its travel, and means for automatically reversing the direction of travel of the grinding wheel at predetermined limits and manually operated means for adjusting the grinding wheel into the thread of the worm.

90. In a machine for grinding worms, the combination of means for revolving the worm about its axis at a predetermined speed, a grinding wheel and means for revolving the same, means for feeding the grinding wheel along the worm and in grinding contact therewith at a speed having a predetermined relation to the speed of revolution of the worm, means for withdrawing a 60 the grinding wheel from the worm at one

end of its travel and for returning it into grinding position at the other end of its travel, means for automatically intercepting the travel of the grinding wheel at predetermined limits, means for automatically indexing the worm while the grinding tool is out of grinding contact with the worm.

91. In a machine for grinding worms, the combination of means for revolving the worm about its axis at a predetermined speed, a grinding wheel and means for revolving the same, means for feeding the grinding wheel along the worm and in grinding contact therewith at a speed having a predetermined relation to the speed of revolution of the worm and means for automatically returning the grinding wheel along the worm and out of grinding contact therewith.

92. In a machine for grinding worms, the combination of means for revolving the worm about its axis at a predetermined speed, a grinding wheel and means for revolving the same, means for feeding the grinding wheel along the worm and in grinding contact therewith at a speed having a predetermined relation to the speed of revolution of the worm, means for automatically returning the grinding wheel along the worm and out of grinding contact therewith and means for automatically indexing the worm while the grinding tool is out of grinding contact with the worm.

93. In a machine for grinding worms, the combination of means for revolving the worm about its axis at a predetermined speed, a grinding wheel and means for revolving the same, means for feeding the grinding wheel along the worm and in grinding contact therewith at a speed having a predetermined relation to the speed of revolution of the worm, means for automatically returning the grinding wheel along the worm and out of grinding contact therewith and manually operated means for adjusting the grinding wheel into the thread of the worm.

94. In a machine for grinding worms, the combination of means for revolving the worm about its axis at a predetermined speed, a grinding wheel and means for revolving the same, means for feeding the grinding wheel along the worm and in grinding contact therewith at a speed having a predetermined relation to the speed of revolution of the worm, means for automatically returning the grinding wheel along the worm and out of grinding contact therewith, means for automatically indexing the worm while the grinding tool is out of grinding contact with the worm and manually operated means for adjusting the grinding wheel into the thread of the worm.

95. In a machine for grinding worms, the

combination of means for supporting and revolving the worm about its axis, a grinding wheel and means for revolving the same, means for producing predetermined relative movement between the worm and the grinding wheel along the axis of the worm, and automatic means for producing grinding contact between the grinding wheel and the worm during the relative movement in one direction and for releasing the grinding contact during the relative movement in the opposite direction.

96. In a machine for grinding worms, the combination of means for supporting and revolving the worm about its axis, a grinding wheel and means for revolving the same, means for producing predetermined relative movement between the worm and the grinding wheel, means for producing grinding contact between the grinding wheel and the worm during the relative movement in one direction and for releasing the grinding contact during the relative movement in the opposite direction, means for automatically indexing the worm while the grinding wheel is out of contact with the worm and means for varying the angle of movement of the work at each indexing of the same.

97. In a machine for grinding the threads of worms, means for holding the work, a grinding wheel movable longitudinally of the work during the grinding operation, means for rotating the work at a speed to maintain the thread in proper contact with the grinding wheel during its grinding movement, means for resetting the grinding wheel for successive grinding operations, and means for indexing the work during the resetting interval.

98. In a machine for grinding the threads of worms, means for holding the work, a rotatable grinding wheel angularly adjustable to accord with the angle of the thread and movable longitudinally of the work during the grinding operation, means adapted to rotate the work at a speed to maintain the thread in proper contact with the grinding wheel during the grinding operation, means for resetting the grinding wheel for successive operations, and means for indexing the work during the resetting interval.

99. In a machine for grinding the threads of worms, means for holding the work, a rotatable grinding wheel angularly adjustable to accord with the angle of the thread and movable longitudinally of the work during the grinding operation, means for rotating the work at a speed to maintain the thread in proper contact with the grinding wheel throughout its length, automatic means for resetting the grinding wheel for successive operations, and automatic means for indexing the work during the resetting interval.

100. In a machine for grinding the threads of worms, work holding means, a rotatable grinding wheel angularly adjustable to accord with the angle of the thread, automatic means for moving the grinding wheel longitudinally of the work during the grinding operation, means for adjusting the grinding wheel to operate on work of various diameters, means for rotating the work at a speed to maintain the thread in proper grinding contact with the grinding wheel during the grinding movement, automatic means for resetting the grinding wheel for successive operations, and automatic means for indexing the work during the resetting interval, said last named means involving a master-gear having teeth corresponding in number to the number of threads on the worm.

101. In a machine for grinding the threads of worms, work holding means, a rotatable grinding wheel angularly adjustable to accord with the angle of the thread, automatic means for moving the grinding wheel longitudinally of the work during the grinding operation, means for rotating the work at a speed to maintain the grinding wheel in proper contact therewith throughout the grinding movement, said means including a master-gear the number of teeth of which is determined by the pitch of the thread to be ground, automatic means for resetting the grinding wheel for successive operations, and automatic means for indexing the work during the resetting interval, said means involving a master-gear having a number of teeth corresponding to the number of threads on the worm.

102. In a machine for grinding the threads of worms, a bed, work holding means thereon, a carriage movable longitudinally of the bed adjacent the work holding means, a rotatable grinding wheel vertically adjustable on the carriage, means for adjusting the angle of the grinding wheel to correspond with the angle of the thread to be ground, a screw threaded shaft for moving the carriage, a gear train connecting the work holder and the screw shaft whereby rotation of the screw shaft rotates the work, said gear train including a removable master-gear whereby rotation of the work maintains the thread and grinding wheel in positive contact during the grinding movement, automatic means for withdrawing the grinding wheel from contact with the work, means for reversing the direction of rotation of the screw shaft to reverse the direction of movement of the carriage, an indexing shaft through operation of which the work may be indexed, means whereby said shaft is operated during the reverse operation of the screw-shaft, automatic means for moving the grinding wheel into contact with the

work, and driving means for operating the said shafts in timed relation.

103. In a machine for grinding the threads of worms, a bed, work holding means thereon, a carriage movable longitudinally of the bed adjacent the work holding means, a rotatable grinding wheel vertically and angularly adjustable on the carriage for setting the grinding wheel at an angle corresponding with the angle of the thread to be ground, a screw threaded shaft for moving the carriage longitudinally, automatic means for moving the carriage transversely of the bed to bring the grinding wheel into and out of contact with the work at the proper intervals, a gear train connecting the work holder and the screw-shaft whereby rotation of the said shaft may rotate the work, said gear train including a removable master-gear whereby rotation of the work maintains the grinding wheel in positive contact with the thread during the grinding movement, automatic means for reversing the direction of rotation of the screw shaft to reverse the direction of movement of the carriage, an indexing shaft through operation of which the work may be indexed, automatic means whereby said indexing shaft is turned during reverse operation of the screw-shaft, and driving means for operating the said shafts in timed relation.

104. In a machine for grinding the threads of worms, a bed, rotatable work holding means mounted thereon, a carriage reciprocatable longitudinally of the bed adjacent the work holding means, a rotatable grinding wheel vertically and angularly adjustable on the carriage whereby the grinding wheel may be set at an angle to correspond with the angle of the thread to be ground, a screw threaded shaft in threaded relation with a fixed part of the carriage whereby rotation of the shaft moves the said carriage longitudinally, a shaft rotated by movement of the carriage, adjustable stop devices on the said last named shaft, means for moving the carriage transversely of the bed to bring the grinding wheel into and out of engagement with the work, a gear train connecting the work holder and the screw shaft whereby rotation of the shaft may rotate the work, said gear train including a removable master-gear whereby the work may be rotated at a speed to maintain the thread in engagement with the grinding wheel during the grinding movement, means for reversing the direction of rotation of the screw-shaft, means for indexing the work during the reverse operation of the screw-shaft, means whereby a stop device may simultaneously reverse the direction of rotation of the screw-shaft and set the indexing means into operation at the finish of the grinding movement and also with-

draw the grinding wheel from engagement with the work, automatic means limiting the operation of the indexing means, and whereby a stop device may simultaneously bring the grinding wheel into engagement with the work and reverse the direction of rotation of the screw-shaft preparatory to the grinding operation.

105. In a machine for grinding the threads of worms, a bed, rotatable work holding means thereon, a carriage reciprocatable longitudinally of the bed parallel with the work holding means, a rotatable grinding wheel vertically and angularly adjustable on the carriage whereby the grinding wheel may be set at an angle to correspond with the angle of the thread to be ground, a screw threaded shaft in threaded relation with a fixed part of the carriage whereby rotation of the shaft moves the carriage longitudinally of the bed, a shaft rotatable by movement of the carriage, adjustable stop devices operated by said shaft, means for moving the carriage transversely of the bed to bring the grinding wheel into and out of engagement with the work, means for rotating the work by the screw-shaft, said means involving a master-gear whereby the work is rotated at a speed to maintain the thread in engagement with the grinding wheel during the grinding movement, an indexing shaft, means whereby rotation of the indexing shaft may rotate the work holder to index the work, said means involving a removable master-gear whereby work with various numbers of threads may be indexed, means whereby the work may be indexed during its rotation by the screw-shaft, a drive-shaft, a plurality of clutch devices by means of which the indexing shaft and the screw shaft may be rotated, the clutch mechanism for the screw-shaft being adapted to alternately set it for operation in a forward or reverse direction, means for moving the carriage transversely of the bed to bring the grinding wheel into and out of engagement with the work, means whereby a stop device actuates the clutch mechanism for both the screw-shaft and indexing shaft, and simultaneously withdraws the grinding wheel from engagement with the work, automatic means limiting the extent of rotation of the indexing shaft, and driving means for the said shafts.

106. In a machine for grinding the threads of worms, work holding means, a grinding device, automatic means for moving the grinding device into and out of engagement with the work, automatic means for moving the grinding device longitudinally of the work while in engagement therewith, automatic means for indexing the work during the interval the grinding device is out of engagement therewith.

matic means for rotating the work to maintain the thread in engagement with the grinding device during the grinding operation, and a differential gear group to one
5 member of which the work rotating means is connected and to the companion member of which the indexing means is connected.

Signed at Cleveland, in the county of Cuyahoga and State of Ohio this 26th day of July, A. D. 1915.
